UNITED STATES PATENT OFFICE.

EDWARD E. HANKEN, OF APPLETON CITY, MISSOURI.

WATER-MOTOR.

1,227,905.

Specification of Letters Patent. Patented May 29, 1917.

Application filed January 18, 1916. Serial No. 72,758.

To all whom it may concern:

Be it known that I, EDWARD E. HANKEN, a citizen of the United States, residing at Appleton City, in the county of St. Clair and State of Missouri, have invented a new and useful Water-Motor, of which the following is a specification.

The present invention appertains to water motors or wheels, and aims to provide a novel and improved apparatus for utilizing the current of water in a river or other stream, as power for operating an electric current generator, mill or other machine, whereby inexpensive power may be had.

The present invention is more in the nature of a rotatable dam, than the ordinary under shot water wheel used in connection with a dam, and relying simply upon the impinging of the water against the paddles. The present wheel is adapted to be mounted in the stream itself, so that its lowermost blades or paddles tend to obstruct the flow of water down the stream, thus acting as a yieldable dam, and affording considerable power. Furthermore, the wheel in acting as a dam, will back up the water, to raise the level thereof, and thus to increase the power and effectiveness of the wheel.

The invention also has for its object the provision of a water wheel of novel and improved construction, whereby it will fulfil the necessary conditions, and it is also the object of the invention to provide novel means for mounting the wheel for vertical adjustment, with its axle continually above the water.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is a plan view of an apparatus employing two water wheels, portions being broken away.

Fig. 2 is a horizontal section on the line 2-2 of Fig. 4.

Fig. 3 is a detail view, partially in section, of the flexible connection between the axle of one wheel and the shaft driven thereby.

Fig. 4 is an enlarged vertical section on the line 4-4 of Fig. 1.

Fig. 5 is a fragmental longitudinal section of one of the water wheels, portions being broken away.

Figs. 6 and 7 are cross sections of the wheel taken on the respective lines 6-6 and 7-7 of Fig. 5.

Fig. 8 is a plan view illustrating another means for mounting the water wheel.

Fig. 9 is a side elevation of the structure illustrated in Fig. 8, the near pier being removed.

Fig. 10 is a longitudinal section illustrating a modification.

As illustrated in Fig. 1, a pair of the water wheels are employed, in coupled relation, but it is to be understood that any suitable number of wheels can be employed to span a stream, and if the stream is navigable, a suitable channel or set of locks can be provided to enable boats to pass the structure. The structure is in the nature of a dam extending transversely of the stream, and embodies a suitable number of piers or foundations 1 of concrete or other appropriate material, between which the water flows. The water wheels are supported between the piers to provide rotatable dams therebetween, tending to stop the flow of water.

Mounted upon the piers 1 are columns 2, each having a metallic shell 3 set on end upon the pier, provided with a filling 4 of concrete united with the pier, to provide a substantial structure. The end piers 1 each have a pair of the columns 2 which are arranged adjacent and parallel with one another, while the intermediate pier 1 has three columns 2, since the intermediate pier must have provision for the axles of the two water wheels. The columns 2 are strengthened by braces connecting them with the piers, and said braces embody metallic shells 5 attached to the shells 3 of the columns, and having the fillings 6 of concrete united with the piers and fillings 4 of the columns. Thus, after the piers are completed by means of coffer dams, or the like, the shells 3 and 5 are placed thereon, and are filled with the concrete, so that the concrete filling or fillings will unite with the piers, and thus provide an integral concrete structure. The upper ends of the columns 2 of each pier are connected by a yoke beam 7, to assist in strengthening the columns.

A water wheel 8 is mounted for rotation

between a pair of piers, and as illustrated comprises a hollow cylindrical drum whose periphery 9 is provided with longitudinal radial blades or paddles 10. The water wheel is made of any suitable size, the length and diameter thereof depending upon the conditions, and has an axle 11 whose terminals are journaled in bearings 12 mounted for vertical sliding movement between the columns 2 of the respective pairs.

In order to guide the bearings 12 for vertical movement, the adjacent walls or members of the shells 3 are constructed of channel irons 13 forming guides. Each bearing 12 is composed of lower and upper sections 12^a and 12^b, respectively, having opposite portions 12^c working within the guides 13. The sections of the bearing are clamped together by bolts, whereby the sections can be detached readily, and the bearing is of cruciform contour in plan, having the portions 12^c which work in the guides 13, and other portions which project from between the guides. The axle 11 is journaled between the sections of the bearing, and the lower section 12^a has a tapered recess or opening 12^d in which is fitted a block 14 providing a seat for the shaft 11.

The blocks 14 have depending lugs 15 fitting in the sockets 16 provided in the upper ends of upstanding or upwardly projecting plungers 17 between the respective columns 2. Each plunger 17 works within a cylinder 18 embedded in the pier 1, and the cylinder may constitute a portion of a hydraulic ram or may be a pressure fluid cylinder, whereby the plunger 17 can be forcibly raised when desired, and under the control of an operator. At any rate, suitable means are provided for raising the plungers 17 when desired, for raising the bearings 12, and the water wheel carried thereby, to lift the wheel out of the water, or to adjust the wheel to different vertical positions, when the water level rises and falls.

As a means for supporting the bearings 12 at a normal position, a column of blocks 19 is provided between each pair of columns 2, and are disposed one upon the other upon the pier, said blocks 19 being of cruciform contour so that certain portions thereof fit within the guides 13, while others project from between the guides. The blocks 19 have central apertures or openings 20 through which the plungers 17 extend. The blocks can be built up to the desired height, the blocks being readily applied and removed. Thus, under ordinary conditions, when the plungers 17 are retracted, the bearings 12 seat upon the blocks 19, and this supports the water wheel at the desired normal position, whereby the lower paddles or blades tend to obstruct the flow of water between the piers. When the plungers 17 are raised, this elevates the wheel, as when the

water level rises during high water, or the wheel can be raised for purpose of repairs. When repairs or adjustments to the shaft or bearings are necessary, the upper sections 12^b of the bearings can be detached, which will let the lower sections 12^a seat upon the blocks 19, and then by raising the plungers 17, the blocks 14 are raised out of the sections 12^a for jacking up the axle 11. This permits the desired repairs to be made conveniently.

Coming to the construction of the water wheel, which is best illustrated in Figs. 5, 6 and 7, there is provided a pair of end hubs 21 secured upon the axle 11, and any suitable number of intermediate hubs 22, the hubs being of disk-form, and being spaced at suitable distances apart. Attached to each of the end hubs 21 is a set of radial spokes 23 of T-iron or other suitable material, and attached to each of the hubs 22 is a set of radial spokes 24 arranged in pairs at opposite sides of the hub 22 and constructed of angle iron or other suitable material. Attached by rivets or otherwise to the outer ends of each set of end spokes 23 is a ring 25 of angle iron or other material, and riveted or otherwise attached to the outer ends of each set of spokes 24 is a ring 26 of T-iron or other suitable stock. The ring 26 is preferably riveted between the outer ends of the pairs of spokes 24. Longitudinal stays or ties 27 of angle iron or other suitable stock connect the rings 25 and 26, and the framework can be otherwise braced to render it thoroughly rigid. The periphery 9 of the drum is constructed of sheet metal, wood, a combination of the two, or other suitable material and is secured upon the rings 25—26 and ties 27, while the ends 9' of the drum constructed of sheet metal, wood, a combination of the two, or the like, are attached to the end spokes 23. One end of the drum is provided with a manhole M, permitting a man to enter the drum for making repairs, and permitting a heater of any suitable sort to be inserted within the drum and hung from the axle for heating the interior of the drum to prevent the accumulation of an ice crust upon the drum, the drum being kept warm during freezing weather.

Secured upon the periphery of the drum are end rings 28 of angle iron surrounding the rings 25, and rings 29, one for each ring 26, are secured upon the periphery of the drum, the rings 29 being of T-iron, and the periphery of the drum being clamped between the rings 25—28 and 26—29. The pairs of rings are preferably secured together to clamp the periphery of the drum therebetween. Attached to the rings 28 are outstanding or radial arms 30 of angle iron, and attached to the opposite sides of each ring 29 are pairs of outstanding angle iron

arms 31, the arms 30 and 31 being in longitudinal alinement at suitable distances apart throughout the periphery of the drum. The blades or paddles 10 which are of sheet metal or other suitable material are attached to the respective arms 30 and 31, and diagonal braces 32 are disposed between the arms of each set to hold the blades in fixed position relative to the drum. Web plates 10' 10 are preferably secured to the arms 30 at the remote ends of the blades 10 to confine the water between them.

In order to brace the intermediate spokes 24 of each set, and to thereby strengthen the drum between its ends, a chordally disposed tie rod 33 is disposed between each pair and has an eye 34 at one end pivoted upon a rivet or other pivot element 35 engaged through one pair of spokes 24, there being one of the rods 33 for each pair of said spokes, and the free terminal of the rod 33 projects between the companion pair of spokes 24 outside of the respective pivot 35 of the next rod 33, as seen in Fig. 7. Washers or blocks 36 are mounted slidably upon the free terminals of the rods 33 and bear against the spokes 24, and nuts 27 are threaded upon the free terminals of the rods 33 and bear against the blocks 36, whereby when all of the nuts 37 are tightened, there is a tendency to draw the spokes toward one another, thereby holding them fast to the hub 22, and strengthening the framework of the drum.

As a means for draining out any water which seeps into or otherwise enters the drum, a funnel-shaped receptacle 38 is attached to one of the tie members 27 between the two sets of spokes, there preferably being one of the receptacles 38 between all of the sets of spokes. Attached to the spout portion of the receptacle 38 is a pipe or hose 39 which is led through one end of the drum. When the wheel is rotated, any water which enters the drum will naturally run to the lower portion thereof, and as the receptacle 38 is moved to and from its lowermost position, it catches the water and raises it with the receptacle 38, and when the receptacle 38 is inclined or moved upwardly sufficiently, the water will drain therefrom through the pipe 39 to the exterior of the drum, thereby ridding the drum of the water.

Annular troughs 40 are attached to the ends of the drum adjacent the periphery thereof, and catch any water which tends to flow from the periphery of the drum or the blades over the ends of the drum, to direct the water downwardly within the troughs 40, and preventing the water from flowing down the ends of the drum to the axle.

The axle 11 of one wheel can be connected to an electric current generator, mill or other machine for operating it by water power, thus affording cheap power. Thus, the axle

11 is connected by a universal joint 41 with a shaft 42 having a telescopic or sliding connection with another shaft 43 which is in turn connected by a universal joint 44 with the shaft 45 upon the shore or at one side of the stream. The universal joints 41 and 44 permit the shafts 42-43 to swing upwardly and downwardly when the axle 11 is raised and lowered, and the sliding connection between the axle 11 and shaft 45 can be extended and contracted as necessary.

The axles 11 of the two wheels are connected, whereby the power derived from both wheels can be taken from one axle, and the axles can be readily connected together by means of sprocket wheels 58 secured thereon and around which is trained an endless sprocket chain 50. Other connections between the axles can be employed. It is to be noted that the axles are offset out of longitudinal alinement, whereby the axles are overlapped, for purpose of connecting them, and to provide a compact arrangement. The intermediate pier has three columns, between which the bearings of the axles are disposed. When there are a large number of wheels, the intermediate piers and allied parts are the same as shown at the center of Fig. 1, which enables any number of wheels to be coupled together, so as to span the stream. If the stream is deeper at certain points than at others, the diameters of the wheels can be made different, or the paddles or blades can be increased or diminished in radial length, as necessary. If the flow at one side of the stream is faster than at the other side, the structure can be arranged at an angle, so as to tend to divert the water to that side where the flow is slowest, thus rendering the flow approximately uniform throughout the width of the stream.

In Figs. 8 and 9, a different means is illustrated for mounting the water wheel so that it can move upwardly and downwardly with its axle 11' continually above the water. Thus, the terminals of the axle 11' are journaled in bearings 47, a pair of links 48 being pivoted, as at 49, to each bearing 47, and the other ends of the links 48 being pivoted, as at 51, to a bearing 50 journaled upon a drive shaft 52. This drive shaft 52 can be mounted for rotation in any suitable manner, as for example, in bearings 53 mounted upon piers 54 between which the water wheel is located. The axle 11' can be connected with the shaft 54 in any suitable manner, in order that the rotation of the wheel will actuate the shaft 52 from which the power can be taken. Thus, sprocket wheels 55 and 56 can be secured to the axle 11' and shaft 52, respectively, and an endless sprocket chain 57 can be trained around the sprocket wheels. The links 48 are swingable upwardly and downwardly to allow the wheel to move vertically, with the wheel trailing in rear of the shaft 130

52, the water flowing in the direction of the arrow in Fig. 8. The links 48 in being pivoted to the bearings 47 and 50 also permit the wheel to shift endwise slightly when necessary, the sprocket chain 57 being of such nature that the sprocket wheels can shift slightly out of a common plane without the sprocket chain jumping off of the sprocket wheels.

10 If the drum construction of wheel is used, the drum renders the wheel buoyant, since the drum will float upon the water, with only the lowermost blades projecting into the water, and the interior of the drum can 15 be heated by any suitable means, to prevent the accumulation of ice thereon, although this feature need not be employed in the warmer climates, in which case the drum is eliminated, and the skeleton frame used 20 without it. If the drum is used, so as to float upon the water, it will hold the axle continually above the water, and this will also hold the wheel in proper position relative to the water which operates it. The 25 wheel is constructed sufficiently large so as not to be injured or put out of order by ice floes, high water, and the like.

Fig. 10 illustrates how a second drum 90 can be provided within the main drum, to 30 provide a heating chamber 91 adjacent the periphery and ends of the main drum, whereby the entire interior of the main drum need not be heated.

Having thus described the invention, what 35 is claimed as new is:

1. In a device of the character described, a pair of piers, a pair of columns carried by each pier, the adjacent sides of the columns having guideways, bearings between the 40 columns and slidably engaging said guideways, a water wheel rotatable between the piers and having an axle journaled in said bearings, means for raising the bearings, and a column of removable blocks fitting between 45 the columns of each pair and having portions engaging said guide ways to prevent the lateral displacement of the blocks, the blocks being held in place when the bearings are seated thereon, and only being removable 50 when the bearings are raised.

2. In a device of the character described, a pair of piers, a pair of columns carried by

each pier, the adjacent walls of the columns being in the form of guide channels, bearings slidably engaging said channels, a water 55 wheel between the piers having an axle journaled in said bearings, a column of blocks upon each pier and having portions fitting in the channels, the blocks having apertures, plungers extending through said apertures 60 for raising the bearings, and cylinders for the plungers embedded within the piers.

3. A water wheel comprising a buoyant hollow drum having blades upon its periphery, a framework for the drum within the same and embodying a set of spokes arranged in pairs, an axle, a hub secured to said axle to which said spokes are attached, rods having certain ends pivoted between the pairs of spokes and projecting between 70 the companion pairs of spokes, and means upon the other ends of said rods engageable with the respective spokes for drawing the spokes together.

4. A water wheel comprising an axle, 75 hubs secured thereon, sets of spokes attached to said hubs, rings attached to the outer ends of said spokes, rings surrounding the aforesaid rings, a drum having its periphery clamped between the first mentioned and 80 second mentioned rings and having ends attached to the end spokes, outstanding arms attached to the second mentioned rings, and longitudinal blades attached to said arms.

5. In a device of the character described, 85 three piers, two water wheels disposed between the piers and having axles offset from one another, three columns carried by the intermediate pier, a pair of columns carried by each of the other piers, a pair of bearings 90 for the adjacent ends of the axles slidable between the columns of the intermediate pier, bearings for the remote ends of the axles slidable between the last mentioned columns, means for adjusting said bearings 95 vertically, and means operatively connecting the adjacent ends of said axles.

In testimony that I claim the foregoing as my own, I have hereto affixed my signature in the presence of two witnesses.

EDWARD E. HANKEN.
